UNITED STATES PATENT OFFICE

2,077,055

BULLETPROOF CAGE FOR BANKS AND THE
LIKEFrancis J. Plym, Niles, Mich., assignor to The
Kawneer Company, Niles, Mich., a corporation
of Michigan

Application August 26, 1933, Serial No. 686,866

5 Claims. (Cl. 20—1.01)

The present invention relates to bullet-proof cages for banks, and the like, and more particularly to a novel construction of bullet-proof cage or booth so positioned that a bandit or other person endeavoring to secure access to the vaults or other compartments where valuables are being kept must pass therethrough.

Among the objects of the present invention is to provide a safety device for use in banking institutions or other places of business wherever there are transactions involving money, securities and/or other valuables.

Another object of the invention is in the provision of a novel bullet-proof cage of a size merely sufficient for the entry of one person, and through which any person or persons desiring access to the location or compartment where the money, securities and/or other valuables are kept must pass. In the preferred embodiment, the cage is provided with a pair of doors or closures, which may be locked from the interior or exterior of the cage whereby should a bandit secure access to the interior of the cage in an endeavor to pass to the rear thereof, he may be trapped therein by an employee, official or other person who has noted his entry into the cage. If the outer door is locked the bandit could not enter the cage. If an employee or official of the banking or other institution passes or is forced into the cage, he can use it as a haven by locking it from the interior, since the cage is bullet-proof.

A further object of the invention is to provide such a cage with a pair of doors or closures so arranged and connected as to prevent the opening of one door or closure without a closing of the other. This arrangement prevents more than one person passing through the cage at one and the same time, since such person must first enter the cage, close the door after him and then open the other door.

Another object of the present invention is to provide a cage or booth which may be formed as a portable unit for use in paying off employees, and readily transported from place to place. In the disclosed embodiment, the cage or booth may consist of two compartments, one having the novel closure arrangement and of a size permitting the entry of but one person, and the other in which that person may transact his business or pay off the employees. This type of structure is admirably adapted for use by paymasters without danger of their being robbed, since the entire unit is bullet-proof and they are beyond personal danger when once inside the cage or booth. This construction would eliminate the necessity of

guards during the period that the paymaster or other person is in the cage. It would further permit an agency similar to those now employed to transport and collect money, securities and/or other valuables by armored cars, to act as paymasters and pay off employees from such a cage or compartment, which could be readily moved from place to place.

A still further object of the invention is in the novel electrical circuit or circuits, which are so related that the opening of one door breaks the circuit and prevents the opening of the second door without a closing of the first mentioned door. The opening of the first door breaks the circuit and this circuit cannot be re-established until that door is closed.

Another and further object of the invention is in the provision of an electrical circuit or circuits adapted to energize a solenoid for retracting a latch bolt and thereby unlocking the door. In the present embodiment such a solenoid is provided for each latch bolt, and an opening of one door breaks the circuit to the other solenoid, and thereby prevents its retraction as long as the other door is open.

The invention further resides in the combination, construction and arrangements of parts and details illustrated in the accompanying drawings, and while there is shown therein a preferred embodiment, it is to be understood that the same is susceptible of modification and change, and comprehends other details, arrangements and constructions without departing from the spirit of the invention.

Further objects are to provide a construction of maximum simplicity, efficiency, economy and ease of assembly and operation, and such further objects, advantages and capabilities as will later more fully appear and as are inherently possessed thereby.

In the drawings:—

Fig. 1 is a view in perspective of the novel cage positioned in the partition in a bank or other financial institution.

Fig. 2 is a fragmentary view in horizontal cross-section through the cage.

Fig. 3 is a perspective view of an alternate form of cage or booth.

Fig. 4 is a view in horizontal cross-section of the construction disclosed in Fig. 3.

Fig. 5 is a diagrammatic view of the electrical circuits controlling the door latch mechanism.

Fig. 6 is a fragmentary view in vertical cross-section through the door operating mechanism.

Referring more particularly to the disclosure

in the drawings, the embodiment selected to illustrate the invention in Figs. 1 and 2 of the drawings, comprises a cage located in the partition A, separating the front and rear of a bank or 5 other financial institution where transactions are carried on involving money, securities and/or other valuables. The cage as well as the partition is bullet-proof, and the cage may form the only means of access to the vaults, tellers' cages 10 or other compartments where such money, securities and/or other valuables are kept.

The cage comprises side walls 1 and 2 and closures or doors 3 and 4. The side walls and doors or closures form a compartment 5, of a 15 size merely sufficient for the entry and reception of but one person. Each door is hinged at 6 and at its opposite edge or side is provided with a knob or handle 7, which when rotated or moved in order to open the door energizes an electrical 20 circuit to a solenoid 8, which when energized retracts the latch bolt 9. Upon an opening of one of the closures or doors from either side thereof the circuit to the opposite door is broken and 25 cannot again be energized or reestablished until the first mentioned door is closed. Thus a person opening one of the doors and entering the cage is precluded from opening the other door until the first mentioned door is closed. This is accomplished by means of contacts in the side rail 30 10 of the door or closure and in the adjacent jamb 11.

The contacts in the side rail of the door and jamb are clearly disclosed in Fig. 5 of the drawings, in which there is set forth a wiring diagram 35 of the circuit or circuits to the doors 3 and 4. As disclosed in this figure, the contact plates 12 and 12a are in the side rails of the doors or closures, while the contact plates 13 and 13a are in the jamb. Current flowing from an outside source 40 passes through the wires 14 and 15. From the wire 14 the current passes through the wires 16 and 16a in opposite directions to the solenoids 8 and 8a, and from there to the wires 19 and 19a to the upper contact button in the plates 13 and 45 13a. When the doors are closed, the current in each passes from the upper contact in the plates 13 and 13a to the upper contact in the plates 12 and 12a, and from there through the wires 20 and 50 20a to the switches 21 and 21a of the handles or latch constructions 7.

Assuming that the switch 21 has been thrown from the exterior or interior of the door 3 by means of a turning of the handle 7, current 55 passes from the wire 20 in this door to the wire 22 and second contact in the plate 12 to the second contact in the plate 13, and from there through wire 23 to the third contact in the plate 13a in the door or closure 4, and from there to the third 60 contact in the plate 12a of this latter door. From this third contact in the plate 12a the current passes through the wire 24 to the switch 21a of this door, and through this switch to the wire 25 and to the fourth contact in plates 12a and 13a, and from the latter through the wire 26 and 65 switch 27a to the line 15, thus closing the circuit and energizing the solenoid 8 in the door 3. The energizing of this solenoid retracts the latch bolt 9 and permits an opening of the door.

70 When the handle 7 on the door 4 is operated from the exterior or interior whereby to throw its switch 21a, current passes from the wire 14, through the wire 16a, solenoid 8a, wire 19a, thence through the upper contacts in the plates 13a and 75 12a, and wire 20a, to the switch 21a. From the

switch 21a the current passes through the wire 20 and the second contacts on the plates 12a and 13a, through the wire 29 to the last contacts on the plates 13 and 12 on the door 3, and from there through the wire 30, switch 21, wire 31, through the third set of contacts on these plates 12 and 13 to the wire 32 and switch 27 to the line 15.

Upon the opening of the door 3 the contact plates 12 and 13 in this door are separated and 10 current cannot flow to the door 4 whereby to energize the solenoid and thereby retract the latch bolt in this latter door. A similar operation takes place if the handle 7 of the door 4 is operated or turned to open this door when the 15 door 3 is closed.

In Fig. 6 is disclosed a vertical section of the latching mechanism or switch 21 of the door 3. As disclosed in this figure, the wire 20 is connected to a contact 33, while the wire 22 is connected to a movable spring contact 34, which is adapted to be brought into contacting engagement with the contact 33 when the handle 7 is moved to open the door, and thereby closing the circuit through the wires 20 and 22. This closing of the circuit through the contacts 33 and 34 is accomplished by means of a pivoted member 35 forming a part of the handle 7. The wire 30 is likewise connected to a contact 36, while the wire 31 is connected to a movable spring contact 37. In this view the handle is shown in the normal locked position of the door, and in which position current can pass through the wires 30 and 31, but not through the wires 20 and 22.

In order that either of the latch bolts 9 may be retracted, it is necessary to energize its respective solenoid. This energizing cannot be accomplished except when both doors are closed and current flows through the wires 20 and 22 of the door 3 or wires 20a and 28 of the door 4. Thus in order 40 to energize the solenoid 8 of the door 3, the handle 7 thereof must be operated to break the contacts 36 and 37 and make the contacts 33 and 34. If door 4 is to be opened from the interior or exterior, its solenoid 8a must be energized by 45 operation or turning of the handle on this door.

Although I have gone into considerable detail in explaining the wiring diagram it is to be understood that numerous changes may be made 50 therein to accomplish the same function and purpose, and that I have disclosed but one operative embodiment for accomplishing this result.

In Figs. 3 and 4 is disclosed an alternate construction of booth or cage 39, provided with closures 3a and 4a leading into a compartment 40. This construction is admirably adapted for the use of paymasters, and the like, although it is adapted for numerous other uses, as will be readily apparent. In this compartment 40 there is provided a window 41, beneath which is positioned a tiltable receptacle 42 for the transfer of money, securities and/or other valuables from one side of the partition to the other. This receptacle may be similar in construction and operation to that disclosed in my Patent No. 1,890,587, of December 13, 1932. A gun port 43 is also provided adjacent the window 41. The entire construction is made bullet-proof so that there is no danger to the occupant while in either compartment of the cage. The arrangement and operation of the doors or closures 3a and 4a is similar to that of the construction disclosed in Figs. 1 and 2, and the wiring diagram is similar thereto, so that it is necessary that both doors be closed before either may be opened from the interior or exterior, and after 70 75 80 85 90 95 98 99 100

such door has been opened it must again be closed to permit an opening of the other. The compartment 44 connecting these doors is of a size sufficient to permit but one person to enter and remain therein while the doors are closed.

From the above description and disclosure in the drawings it will be readily apparent that the invention comprehends a novel safety arrangement in the form of a bullet-proof cage or booth, preventing the entry of more than one person at a time. It will prevent a bandit from forcing an officer or employee of a bank or other financial institution to pass ahead of him through the cage and compel such official or employee to permit the bandit to pass therethrough. If the bandit enters the cage or compartment, the electrical circuit may be broken by one of the switches 27 or 27a provided for such purpose, and which may be concealed so that no one but the officials or employees of the bank know thereof. One may be exterior of the cage while the other may be in the interior. After the current has been cut off or the circuit opened neither door may be opened, and the bandit would be trapped therein. If the official or employee enters or is made to pass therein he likewise can open the circuit by a switch concealed in the cage, and since the construction is bullet-proof he cannot be molested. If there are a number of bandits, the official or employee may permit some or all of them to pass therethrough, and when once behind the partition he may open the circuit and prevent their escaping. Usually, however, the official or employee is made to open the safe or vault, and regardless of whether the official or employee passes therethrough first, last or therebetween, he must pass through the cage, and when once therein he is protected.

Having thus disclosed the invention, I claim:—

1. A safety device for protecting a teller, paymaster or other person handling money and/or other valuables in his work, comprising a member divided into two compartments, the one being of a size sufficient to permit but one person to enter and the other of a size to permit said teller, paymaster or other person to carry on his work, said first mentioned compartment having a door for securing access thereto and a door connecting said compartments, said doors being so constructed and connected that a person opening the first mentioned door cannot open the second door as long as the first door remains open, and electrically operated means for unlatching and permitting an opening of either of said doors, but upon an opening of one preventing an unlatching of the other.

2. A safety device for protecting a teller, paymaster or other person handling money and/or other valuables in his work, comprising a portable member which may be easily transported to the place where payment is to be made, said member being divided into two compartments, the one being of a size sufficient to permit but one person to enter and the other of a size to permit said teller, paymaster or other person to carry on his work, said first mentioned compartment having

a door for securing access thereto and a door connecting said compartments, said doors being so constructed and connected that a person opening the first mentioned door cannot open the second door as long as the first door remains open, and electrically operated means for unlatching and permitting an opening of either of said doors, but upon an opening of one preventing an unlatching of the other.

3. A safety device for protecting a teller, paymaster or other person handling money and/or other valuables in his work, comprising a portable member which may be used as an armoured car or the like divided into two compartments, the one being of a size sufficient to permit but one person to enter and the other of a size to permit said teller, paymaster or other person to carry on his work, said first mentioned compartment having a door for securing access thereto and a door connecting said compartments, said doors being so constructed and connected that a person opening the first mentioned door cannot open the second door as long as the first door remains open, electrically operated means for unlatching and permitting an opening of either of said doors, but upon an opening of one preventing an unlatching of the other, and means in said second compartment for locking both doors.

4. A bullet-proof compartment providing the means for entry between the front part of a bank or other institution dealing in money, securities and/or other valuables, and the back part thereof where such money, securities and/or other valuables are kept, closures in said compartment permitting entry into said compartment and therethrough, a handle for each of said closures, and electrically operated means adapted to unlatch and permit an opening of one of said closures when its handle is moved to open position, but upon such unlatching and opening of said closure, prevents an unlatching of the other closure, said compartment being of such size that only one person may occupy the same so that it will be impossible for a bandit to force a bank employee or the like into said compartment with him.

5. A bullet-proof compartment providing the means of entry between the front part of a bank or other institution dealing in money, securities and/or other valuables, and the back part thereof where such money, securities and/or other valuables are kept, closures in said compartment permitting entry into said compartment and therethrough, an electrical circuit connecting said closures in series whereby an opening of one of said closures breaks the circuit to the other and prevents its being opened as long as the first mentioned closure remains open, and means for opening the circuit to prevent a burglar or other person from entering the compartment or for trapping such person after he has entered the same, said compartment being of such size that only one person may occupy the same so that it will be impossible for a bandit to force a bank employee or the like into said compartment with him.
